UNITED STATES PATENT OFFICE.

ETHAN W. FRANZ AND SIDNEY TATE, OF EAST CLEVELAND, OHIO.

ADJUSTABLE SHORE POST.

Application filed July 14, 1921. Serial No. 484,560.

To all whom it may concern:

Be it known that we, ETHAN W. FRANZ and SIDNEY TATE, citizens of the United States, and residents, respectively, of East 5 Cleveland, in the county of Cuyahoga and State of Ohio, and East Cleveland, in the county of Cuyahoga and State of Ohio, have invented a certain new and useful Improvement in Adjustable Shore Posts, of 10 which the following is a full, clear, and exact description.

In the laying of concrete floors it is customary to erect false work for receiving and 15 temporarily supporting the fresh concrete. This false work commonly includes upright shore posts, stringers supported thereby, joists which are laid upon the stringers, and a deck built upon the joists.

After the concrete has been set to such an 20 extent that it may be expected to sustain its own weight, the false work is taken down. In the method commonly followed the stringers are lowered a sufficient distance 25 and the joists are tipped over, which allows the deck to descend out of contact with the concrete floor. This deck and joists and stringers are then removed, but the shore posts are allowed to remain standing. In fact, when the false work is erected their 30 upper ends are allowed to project through the deck so as to be flush with the upper surface thereof; and therefore when the deck and the supports therefor are removed and the shore posts left standing, said shore posts will engage the fresh concrete and 35 prevent it from sagging before it is thoroughly hardened.

The erection of this false work including the necessary accurate levelling of the deck, 40 and the alignment of the upper ends of the shore posts with the top of the deck, and the subsequent removal of the false work involves a very large labor cost, and very frequently a very considerable destruction of material employed in the false work.

The object of this invention is to greatly 45 reduce the cost and loss incident to the erection and removal of this false work. The invention by which this end is attained resides in the shore posts shown and their adjuncts, and consists in the construction and combination of parts shown in the drawing and hereinafter described and pointed out definitely in the appended claims.

50 In the drawing, Fig. 1 is a vertical sectional elevation of false work which sup-

ports a freshly laid concrete floor, including shore posts embodying the invention. Fig. 2 is a front elevation on an enlarged scale of a joist hanger and part of a shore 60 post to which said joist hanger is secured; Fig. 3 is a side elevation of the construction shown in Fig. 2; Fig. 4 is a side elevation partly sectioned of the clamp mechanism by means of which the shore post body 65 is adjustably connected with the shore post leg; Fig. 5 is a sectional plan view in the plane of line 5—5 on Fig. 4 showing said clamping mechanism; Fig. 6 is a transverse 70 sectional view through one of the shore posts in a plane indicated by line 6—6 on Fig. 1, and Fig. 7 is a front elevation of one of the upper ends of one of the shore posts which is especially contrived for supporting a concrete beam instead of false work.

Each shore post is formed of a post body 10 having a longitudinal hole 11 extending from the bottom of the post upward as far as may be necessary or desirable. Each post also includes a leg 12 which telescopes into 80 the post body from the bottom thereof; a clamping device 20 which supports the body and is clamped at any desirable point along the leg 12. The post also includes a foot piece 13 which is below and in axial alignment with the leg 12 and is adjustably connected thereto by a turn buckle which engages with the oppositely threaded adjacent ends of the foot piece and leg, which parts are cylindrical and are preferably made of 85 ordinary pipe of suitable diameter.

The post body 10 is preferably made of two pieces 10^a, 10^b, of wood, nailed together, said pieces having in their engaging faces semi-cylindrical longitudinal grooves which 90 when the two pieces are nailed together form the longitudinal cylindrical hole which receives the leg 12.

The post body and leg are connected by a self-adjusting automatic clamp, represented 100 in its entirety by 20. This clamp includes a base plate 21 upon which the lower end of the post body is supported, said lower end being fitted into a recess in the upper side of said base plate. This base plate is formed 105 with two integral downwardly extended and oppositely inclined arms 23, in each of which is a slot 24. There are two cam levers 25 which respectively pass through these slots 24. These are enlarged at their 110 lower ends so that the lower ends can not pass through the slots, and some means, as
